(57) **CLAIM**

The ornamental design for a combination hemodialysis device with dialysate generator as shown and described.

DESCRIPTION

FIG. 1 is a front perspective view of a hemodialysis system with dialysate generator of our design;

FIG. 2 is a rear perspective view thereof;

FIG. 3 is a front elevation view thereof;

FIG. 4 is a rear elevation view thereof;

FIG. 5 is a left elevation view thereof;

FIG. 6 is a right elevation view thereof;

FIG. 7 is a top plan view thereof;

FIG. 8 is a bottom plan view thereof;

FIG. 9 is an exploded front perspective view thereof; and,

FIG. 10 is an exploded rear perspective view thereof.

The broken lines represent unclaimed subject matter and form no part of the claimed design.

1 Claim, 10 Drawing Sheets
